UNITED STATES PATENT OFFICE.

CLARENCE D. PLATT, OF BRIDGEPORT, CONNECTICUT.

METER-TESTING-SWITCH CONSTRUCTION.

1,240,363.

Specification of Letters Patent. Patented Sept. 18, 1917.

Application filed December 4, 1916. Serial No. 134,856.

To all whom it may concern:

Be it known that I, CLARENCE D. PLATT, a citizen of the United States of America, residing at Bridgeport, Conn., have invented 5 a new and useful Meter-Testing-Switch Construction, of which the following is a specification.

My invention relates particularly to what is commonly termed an entrance switch and 10 a connection by means of which the meter which is normally in the circuit may be conveniently tested without breaking the circuit.

Figure 1, is a front view of a switch embodying the improvements of my invention 15 and showing the meter testing connections in place.

Fig. 2, is a side view and section on the plane of the line 2—2 of Fig. 1.

20 Fig. 3, is a rear view of the lower part of the switch showing the sockets for the meter testing connections.

Fig. 4, is a detail view of one of the conductor terminals for the meter testing connection.

Fig. 5, shows details of the hand-piece for the meter testing connection.

In the particular form of switch illustrated 10 indicates an insulating base; 11, 11 are the binding posts or terminals for the main line conductors; 12, 12 are the binding posts or terminals for the branch conductors; 13, 13 are switch terminals connected to the binding posts 11, 11 and serving as 15 supporting posts for the hinged blades 14, 14; 15, 15 are stationary switch jaws for receiving the ends of the switch blades; 16, 16 indicate the center fuse plug contacts connected to the jaws 15, 15 respectively; 17, 17 20 are screw sockets for the fuse plugs connected respectively to the binding posts 12, 12. The switch is opened and closed by means of an insulating hand-piece 18 which connects the two upper ends of the switch 25 blades 14, 14.

Metallic sockets 20, 20 and 21, 21 located in the insulating base between the blades 14, 14 and below the handle 18 are connected respectively to the switch terminals 13 and 15 30 by strips 22, 22 and 23, 23.

The connection to the test meter is effected by means of a special plug and conductors consisting of a hand-piece 25 and terminals 26 and 27 having the wires 28 and 29 lead-

ing to the test meter. Each wire is preferably protected by an insulating sheath 30. Each terminal such as 26, is preferably split so as to be yielding and effect a friction-tight connection in one of the switch sockets. The hand-piece 25 is preferably formed of two 55 parts with a passage 31 for the terminal 26 and a groove 32 for the collar 33. Preferably the terminal 26 and collar 33 are smaller in size than the passage 31 and the groove 32 so that the terminal 26 may have a 60 limited movement relative to the hand-piece to permit the terminals to fit more easily in the sockets without binding. The hand-piece is also provided with a recess 34 for the sheath 30 which recess is preferably 65 somewhat smaller in diameter than the sheath so that the sheath can be clamped tightly when the screw 37 is set up. Grooves such as 35 and 36 are preferably provided to allow the material of the sheath to bulge out 70 and thus be gripped more securely to prevent its withdrawal.

It will be seen from the foregoing and the accompanying drawings that the construction is such that the meter connecting plugs 80 may be inserted into the switch base sockets before opening the circuit through the switch and without distributing the electrical condition in the branch line. When the connecting plugs have been inserted in the 85 base, the switch may be then opened so as to throw the current through the meter for the purpose of testing. Obviously this opening of the switch does not affect the interior line. The advantages of this will be apparent to 90 those acquainted with this art.

It is obvious, with this construction, that the poles of the switch may be connected to a meter in different ways which is important as meters differ in construction. In this 95 construction each pole of the switch has a separate connection which may be attached to any binding screw of any meter.

I claim:

A meter testing switch, comprising an insulating base, a pair of spaced apart switch posts on the insulating base, a complementary pair of switch contacts spaced apart on the base and disposed each in line with one of the switch posts, switch blades hinged to 100 the switch posts and arranged each to engage one of the switch contacts, contact sockets 105 closely spaced in pairs alongside each of

the switch blades and said sockets being disposed in the space bounded by the switch blades and sunk in the material of the insulating base with their outer plug receiving ends close to the outer face of the insulating base to thereby enable the insertion of testing plugs into such sockets between the

switch blades and the opening of the switch over the tops of said testing plugs, and connecting straps at the back of the insulating base connecting the testing sockets to the switch posts and contacts respectively. 10

CLARENCE D. PLATT.
